DYNAMIC DEAERATOR AND WATER HEATER

Henry J. Schneider, Quincy, Mass.

Application February 26, 1940, Serial No. 320,826

3 Claims. (Cl. 261—89)

This invention relates to a combined deaerator and water heater and it consists in the constructions, arrangements and combinations herein described and claimed.

5 It is the object of my invention to provide a deaerator heater in which the water passes through a substantial number of tubes, the latter being heated by steam, and in which water from the tubes is discharged, spread and agitated by 10 means of steam actuated turbines, the dynamic action permitting liberation of air, oxygen or impurities which are a detriment to steam generation, as well as appliances.

Specifically, it is an object of the invention to 15 provide a deaerator embodying a plurality of rotatable units for discharging water over a considerable area, and in which each unit includes a turbine positioned upon opposite sides of a common steam pipe, the pipe having nozzles for 20 discharge of steam against the turbine to impart rotation thereof.

It is also an object of the invention to provide 25 a deaerator consisting of a plurality of units mounted upon a base which may be readily removed from the deaerator casing for repair of the parts.

Additional objects, advantages and features 30 of invention will be apparent from the following description, considered in conjunction with the accompanying drawings, in which

Figure 1 is a cross section of my dynamic deaerator and water heater.

Figure 2 is a longitudinal sectional view.

Figure 3 is a plan view of unit A of Figure 1.

35 Figure 4 is a cross section on the line A—A of Figure 1.

In carrying out my invention, I provide a casing 30, in the present instance being shown as of cylindrical form, having a water inlet 21 and 40 outlets 22. A bank of water pipes 18 are connected between the inlet 21 and outlet 22, and as shown, the pipes are positioned in the uppermost portion of the casing. An exhaust port 1 is provided in the casing, above the pipes 18, 45 allowing steam to pass therethrough to a steam condenser, not shown. The outlet 22 includes a pair of water pipes 3 and 19 extended longitudinally of the casing immediately below the lowermost pipes 18 and spaced a like distance 50 from the axial center of the casing as best seen in Figure 1.

A steam pipe 15 is arranged through the longitudinal center of the casing, having an inlet 25 and an exhaust outlet 26. A platform 13 is 55 movably supported within the casing 30, in the

present instance, longitudinally extended lugs 31 slidably receiving the platform. The casing includes removable end walls 32, permitting insertion and removal of the platform. The platform 13 is perforated, as shown in Figure 2, permitting free passage of water to the lower portion of the casing, and a perforated plate 20 is positioned below the platform 13, the latter plate serving as a strainer, to prevent foreign matter passing into the lower portion of the casing. 10 This plate is also removable for cleaning purposes. The lower portion of the casing has a pipe 27 for connection with a suction means of a boiler feed pump not shown, and also has a drain connection 28. 15

Upon the platform 13 there are mounted a plurality of upright rotatable shafts 10 supported in bearings 11 and 12, the shafts 10 being spaced longitudinally along the platform in pairs upon opposite sides of the steam pipe 15. Each shaft 20 10 has fixed thereon a turbine wheel 16, the vanes of which are presented to respective steam nozzles 14 of the pipe 15.

The deaerator units are of identical construction and a description of one will be sufficient for 25 an understanding of the device. Above the turbine wheel 16 there is rigidly secured to the shaft 10 an annular disk 9, the latter having a perforated periphery and an inwardly turned upper edge. 30

Concentric with the shaft 10, there is an annular spray pipe 2 having communication with water pipes 3 or 19, as the case may be. Radially disposed gusset plates 5, 6, 7 and 8 are fixed to the pipe 3 or 19, extended downwardly and have 35 secured at their ends a perforated annular disk 4. The disk 4 remains stationary and is additionally supported by reason of engagement of the shaft 10 within the bearing 11.

The disk 9 has a multiplicity of apertures 40 formed in the periphery of the upturned edge in order that water may be discharged centrifugally, under rotation of the disk, and in order that the water discharged may thoroughly be broken up, there is provided a cylindrical deflector plate 17. The plate 17 may be supported from the platform in any approved manner.

In use, water passes through the pipes 3 and 19, through the spray pipes 2 downwardly on to the disk 4, through the apertures of the disk 50 and into the rotatable disk 9. Steam enters through pipe 15, being discharged through respective nozzles 14 so that the steam impinges against the vanes of the turbine 16, causing rotation of the disk 9, with consequent discharge 55

of water through the apertures of the disk into forcible contact with the deflector plate 17. Thus the water will be thoroughly agitated and broken up in a fine mist so that impurities are released.

5 While I have shown and specifically described my invention, this is by way of illustration only, and I consider as my own all such modifications as fairly fall within the scope of the appended claims.

10 I claim:

1. In a dynamic deaerator and water heater, a casing having a multiplicity of water pipes in an upper portion thereof, inlet and outlet means for the pipes, said casing having a steam exhaust port above the pipes, a pair of water pipes connected with the outlet means of the water pipe, said pair of water pipes being extended into the casing in parallel spaced relation, a plurality of annular spray pipes spaced longitudinally of and connected with said respective pair of pipes, a perforated disk suspended from each of said spray pipes, a perforated platform within the casing, a shaft revolvably supported on the platform axially beneath each of said disks, a perforated disk beneath the first disk and fixed to the shaft, a turbine wheel fixed to each shaft, a steam pipe within the casing and positioned adjacent the turbine wheel and said steam pipe

having nozzles for discharge of steam against the turbine wheel.

2. In an dynamic deaerator and water heater, a casing having a multiplicity of water pipes in an upper portion thereof, inlet and outlet means 5 for the pipes, said casing having a steam exhaust port above the pipes, a pair of water pipes connected with the outlet means of the water pipes, said pair of water pipes being extended into the casing in parallel spaced relation, a plurality of 10 annular spray pipes spaced longitudinally of and connected with said respective pair of pipes, a perforated disk suspended from each of said spray pipes, a perforated platform within the casing, vertically disposed rotatable shafts on the platform, one shaft being axially positioned beneath each of said disks, a disk fixed to each shaft, said disk having an annular perforated wall, a turbine wheel on each shaft, a steam pipe within the casing and positioned longitudinally between the 15 upright shafts, said steam pipe having a nozzle in operative relation to respective turbine wheels, and an annular deflector plate circumscribing said disks.

3. The structure of claim 2 in which the casing is provided with detachable end walls and said platform is removable from the casing.

HENRY J. SCHNEIDER.
